METHOD OF AND APPARATUS FOR REACTIVATING CHARCOAL

Application filed December 31, 1925. Serial No. 78,704.

The present method and apparatus, while capable of a fairly wide range of utility in the arts, are peculiarly suited for the reactivation or revivification of charcoal. Although various kinds of charcoal might be treated by the method, it is peculiarly adapted for the treatment of bone char, such as is commonly used for decolorizing sugar in the process of sugar refining, or for decolorizing or purifying oil or other substances.

In the sugar refining process for instance, bone char is used as an adsorbent for removing foreign organic matter from the sugar being treated. It is customary to subsequently subject the char to a reactivating process in order to remove this organic matter and render the char fit for reuse.

The conventional methods used in reactivating have been unsatisfactory for a number of reasons. In the first place, the methods are expensive due to the fact that externally fired kilns are used and high temperatures maintained. In the second place, the treatment which the char undergoes is an undesirable and highly inefficient one. The char is ordinarily passed through the highly heated kiln in the presence of insufficient air to support combustion, and the organic matter which has been adsorbed by the char, is distilled off, resulting in a heavy carbon deposit on the surface of the char which is subsequently burned off in a rather superficial manner.

By the use of my improved process and apparatus, the method is rendered much more economical, and the reactivated char which results from the method is of a better quality.

In accordance with a preferred embodiment of the present invention, the kiln is internally fired, and the gases are recirculated, effecting a considerable saving in fuel, also the process is carried out at a rather low temperature and the char in its passage through the kiln encounters sufficient air to support actual combustion. Thus the organic matter is actually burned out of the char rather than distilled off, no carbon deposits are formed, and the treated char is more thoroughly re-

activated and entirely free from clogging carbon deposits on its surface.

The invention may be more fully understood from the following description in connection with the accompanying drawing which is a somewhat diagrammatic view mainly in longitudinal section through a reactivating apparatus embodying the present invention, and well suited for carrying out the method.

In the accompanying drawing I have used the reference character 10 to designate a suitable base upon which an inlet chamber 11 is supported. An inclined rotary kiln 12 which may be of conventional construction has bearings at its upper end in the walls of the inlet chamber 11, and at its lower end in one wall of a fire box 13. Conventional driving mechanism may be employed for rotating the kiln, and has been illustrated as a driven pinion 14 supported upon a base 15 and meshing with a ring gear 16 fixed to the kiln. Supplemental supporting and driving means such as the friction rollers 17 may also be employed. The kiln is provided with the usual number of longitudinally extending flights 18 for thoroughly tumbling and agitating the char as the latter is passed through the kiln.

A vertical baffle wall 19 in the fire box protects the discharge end of the kiln from receiving directly radiated heat from the burner 20. This burner may use either gas or oil, and in any event is controlled by some means which can be manually or automatically regulated for supplying air to the fuel mixture. As shown, the burner is suitable for gas, including a gas pipe 21 and an air pipe 22 the latter being provided with a controlling valve 23 for predetermined the amount of air delivered with the fuel mixture at the burner. In all cases more air is delivered than is actually necessary to support combustion at the burner, since this air is also used for supporting combustion of the char passing through the kiln.

From the chamber 11 there rises a flue 24 preferably equipped with an automatic damper 25 which is controlled by the pressure in chamber 11. This damper may con-

sist merely of a suitably weighted disc in the flue. The char or other material to be treated is delivered through a chute 26 to the upper inlet end of the kiln, and may be brought to the chute by a screw conveyor 27, or any other suitable mechanism.

Reference character 28 has been used to designate an air recirculation pipe extending from the upper end of chamber 11 back to the fire box 13. A suitable fan or blower 29 in the pipe maintains a positive recirculation of gases back to the fire box, and the pipe may be controlled by a damper 30 introduced between the chamber 11 and the fan.

The heated char discharging from the lower outlet end of the kiln, drops into a chute 31, and passing under a gate valve 32, is subjected to a cooling spray of water from any number of spray heads 33 mounted in steam escape pipes 34. Flap valve 32 prevents the passage of steam upwardly into the fire box, and the cooled char passes under another gate valve 35 and through a chute 25 36 into a receptacle or storage bin (not shown).

The method may be outlined substantially as follows. The char to be reactivated or revivified is discharged through the chute 26 into the upper end of the kiln, usually in a rather moist condition. The air supply is so regulated that the hot gases and products of combustion passing through the kiln from the fire box will actually support combustion of the organic matter which has been adsorbed by the char. Due to the presence of blower 29 and damper 25, there will be a recirculation of gases back through the recirculation pipe 28 to the fire box. The damper 25 of course, automatically opens to relieve pressures in the recirculation system, and when recirculation is undesirable, it will be a very easy matter, not only to stop the recirculation by closing damper 30, but to quickly cool the kiln by the action of fan 29.

The temperature in the kiln is maintained relatively low, that is to say, approximately between 400° and 800° Fahrenheit. The char in its passage through the kiln is agitated and tumbled by the flights 18, so that by the time the char has reached the discharge end of the kiln, the entire surface of the mass of material will have been properly exposed to the air and reactivated by the burning out of the organic matter as above described. The hot char coming down the chute 31 and under the gate valve 32 is properly cooled by the water spray at 33, and passes at a relatively low temperature through chute 36 to the storage bin or other receptacle.

It is to be noted that by recirculating the gases in the system I may be able to effect a considerable economy of fuel, and to maintain a substantially uniform temperature throughout the entire length of the kiln. It

is to be noted however, that this method does not necessarily comprehend the recirculation of gases, because I may effect considerable economy over present processes even without the recirculation feature. One improved feature of the method whether recirculation is used or not, is the actual burning out of the organic matter as opposed to the usual methods which result in a distilling rather than a burning.

While I have illustrated one efficient apparatus for carrying out the method, it will be understood that various changes might be made both in the method and apparatus without departing from the spirit and scope of the appended claims.

I claim:

1. A method of reactivating charcoal laden with adsorbed organic matter which includes the step of slowly passing the charcoal through a kiln, subjecting it in its passage through the kiln to a continuous recirculation of pre-heated hot gases through the kiln which will support the combustion of the organic matter.

2. A method of reactivating charcoal laden with organic matter which includes the steps of passing the charcoal through an internally fired kiln in which gases are flowing in a direction opposite to the direction of movement of the charcoal, tumbling the charcoal in the kiln to expose all of the surfaces thereof to the gases, and supplying sufficient air to the gases passing through the kiln to support combustion of the organic matter in the char, the gas pressure in the kiln being below a predetermined amount.

3. A method of revivifying bone char laden with adsorbed organic matter which includes the steps of maintaining a relatively rapid continuous circulation of hot air laden gases in a closed circuit, and passing the char relatively slowly through part of the circuit to burn the organic matter out of the char.

4. A method of reactivating charcoal laden with adsorbed organic matter which includes the steps of slowly passing the charcoal through a kiln while maintaining through the kiln a continuous relatively rapid recirculation of preheated hot gases containing only sufficient oxygen to support the slow combustion of the organic matter.
